UNITED STATES PATENT OFFICE.

JOSEPH LEVENTRY, OF JOHNSTOWN, PENNSYLVANIA.

RAILWAY-CROSSTIE.

1,354,258.

Specification of Letters Patent. Patented Sept. 28, 1920.

Application filed November 18, 1919. Serial No. 338,808.

To all whom it may concern:

Be it known that I, JOSEPH LEVENTRY, a citizen of the United States, residing at Johnstown, in the county of Cambria and 5 State of Pennsylvania, have invented certain new and useful Improvements in Railway-Crossties, of which the following is a specification.

This invention relates to improvements in 10 railway cross ties having novel means for gripping rails.

An important object of this invention is to provide a railway tie having means whereby rails may be securely anchored to the tie 15 without the necessity of employing rail spikes.

A further object of this invention is to provide a rail tie including a pair of sections 20 slideable with relation to each other and having upstanding flanges or lugs adapted to be brought into rigid engagement with the base and web of the rail for securing the rail in position and for bracing the same against rail spreading.

25 A further object of this invention is to provide a rail tie having novel means for gripping and supporting rails of various sizes without changing the construction of the tie.

30 A further object of this invention is to provide a rail tie which is of highly simplified construction, few in parts and cheap to manufacture.

Other objects and advantages of the invention will be apparent during the course 35 of the following description.

In the accompanying drawing, forming a part of this application and in which like numerals are employed to designate like 40 parts throughout the same,

Figure 1 is a side elevation of the improved tie in use,

Fig. 2 is a horizontal section taken on line 2-2 of Fig. 1,

45 Fig. 3 is a group perspective of the base sections of the tie,

Fig. 4 is a perspective of a combined wedge and brace element embodied in the invention,

50 Fig. 5 is a vertical transverse section taken on line 5-5 of Fig. 4.

In the drawing wherein for the purpose of illustration is shown a preferred embodiment of the invention, the numerals 10 and 55 11 designate a pair of metallic base sections slideable with relation to each other and

having their inner longitudinal edges arranged in parallel relation. As illustrated in Figs. 1 and 2, the intermediate portions of the sections 10 and 11 are provided with 60 upstanding flanges 12 and 13 respectively, which are adapted to engage the webs 14 of rails 15 mounted upon the base sections. With particular reference to Figs. 2 and 3, it will be noted that the upstanding flanges 65 12 and 13 are flatly in contact so as to form mutual bracing elements to support the rails, whereby the same are enabled to withstand the side thrust as the result of traffic. The outer end portions of the flanges 12 and 13 70 are recessed, as indicated at 16, for snugly receiving the base sections 17 of the rails. Each base section is provided along its inner longitudinal edge and rearwardly of the upstanding flange of that section with 75 an upstanding lug 18 which cooperates with the upstanding flange of the other section in securing the rail in position. The inner portions of the upstanding lugs 18 are recessed, as indicated at 19, for receiving the outer 80 portions of the rail bases 17. When the upstanding lugs 18 and the coacting flanges 12 and 13 are in engagement with the webs and bases of the rails, the rails are effectively braced and anchored to the tie so that spreading or bending of the rails is eliminated to 85 a high degree.

As particularly illustrated in Fig. 3, each base section is provided along its longitudinal edge in advance of each upstanding 90 flange with an upstanding elongated bar or plate 20 which is extended beyond the adjacent end of the base section and is bent upon itself in parallel relation to the tie section for forming an arm 21. In thus 95 bending the upstanding elongated plate 20 a U-shaped member is provided for slidably receiving the lug 18 of the other base section when the sections are arranged in the position illustrated in Fig. 2. It will be 100 noted with reference to Fig. 2 that the rear end portion of each lug 18 is slidably received within the lug-receiving member of the other section and when one base section is moved longitudinally with relation to the 105 other section the rail is tightly gripped by the lugs 18 and the flanges 12 and 13. A locking key or wedge 22 is adapted to be received within the U-shaped lug-receiving member and is tapered at its forward end, 110 as indicated at 23, for engaging the rear end of the adjacent lug 18. When the key

22 is hammered downwardly, the adjacent lug 18 is forced into rigid engagement with the adjacent rail for securely engaging the same. The tapered forward end 23 of the 5 key 22 increases the pressure on the lug as the key is forced downwardly and therefore the pressure exerted by the lugs 18 may be varied by properly positioning the wedge. The wedge 22 is formed from a single blank 10 of metal having a transverse incision which provides bracing arms 24 bent downwardly on opposite sides of the body of the wedge and in parallel relation to the same for engaging the outer sides of the U-shaped lug- 15 receiving member, whereby the lug-receiving member is prevented from spreading when the wedge is applied. Obviously one depending arm of each wedge is disposed in advance of the other so that the free end 20 portion of the arm 21 is effectively prevented from being bent away from the remaining portion of the elongated plate 20.

When it is desired to anchor the rails to the tie, the base sections 10 and 11 are so 25 positioned with relation to each other that a considerable space is provided between the adjacent ends of the lugs 18 and the sections 12 and 13. This permits of the arrangement of the rails between the ends of 30 the lugs 18 and the sections 12 and 13 preparatory to bringing the lugs and the flanges into gripping engagement with the rails. In so arranging the base sections, each lug 18 is positioned within the U-shaped lug- 35 receiving member of the other section and in spaced relation to the inner portion of the same. The wedge members 22 are now inserted between the sides of the U-shaped lug-receiving members and are engaged 40 with the rear ends of the lugs preparatory to forcing the same into rigid engagement with the rails. This inner movement of each lug 18 also forces the sections 12 and 13 into rigid engagement with the inner 45 sides of the rails since both the lugs and flanges are rigidly associated with the base sections. When the keys 22 are hammered downwardly, the arms 24 of the same engage the outer sides of the U-shaped lug-receiving members whereby the same are prevented from widening as the result of strain. The depending arms 24 of the wedges also 50 facilitate the removal of the wedges when it is desired to replace the rails or take up 55 the same.

By this construction the rails are firmly anchored to the tie without the necessity of employing spikes or bolts.

It is to be understood that the form of 60 the invention herewith shown and described is to be taken as a preferred example of the same and that such minor changes in arrangement and construction of parts may be made as will remain within the spirit

of the invention and the scope of what is 65 claimed.

Having thus described the invention, what is claimed is:-

1. A rail tie including a pair of base sections arranged in parallel relation and slid- 70 able with relation to each other, a rail-engaging member carried by the intermediate portion of each base section and having a recess adapted for receiving the base of a rail, a second rail-engaging member carried 75 by each base section rearwardly of the first-named rail-engaging member of that section and coöperating with the first named rail-engaging member of the other section for engaging a rail, a U-shaped member carried by one end of each base section, and a wedge received within each U-shaped member 80 and adapted for engaging the adjacent second named rail-engaging member for rigidly engaging the same and the first named 85 rail-engaging member with a rail, each wedge being provided with sides engaging the outer sides of each U-shaped member for bracing the same.

2. A rail tie including a pair of base sections arranged in parallel relation, an up- 90 standing flange carried by each base section, a lug carried by each base section in spaced relation to the flange of that section and coöperating with the flange of the other section for gripping a rail, a combined 95 wedge and lug-receiving member carried by each base section, and a wedge received within each combined wedge and lug-receiving member and engaging the rear end 100 of the adjacent lug for forcing the same and the coöperating flange into engagement with a rail.

3. The combination with a pair of parallel base sections having intermediate up- 105 standing flanges along their inner longitudinal edges, said flanges having their op- posed sides flatly in contact, lugs carried by said base sections and coöperating with said flanges for engaging parallel rails, a wedge support carried by each base section and slidably receiving the adjacent lug, and a wedge carried by each wedge support for forcing said lugs and said flanges into rigid 110 contact with said parallel rails.

4. The combination with a pair of base sections having means for engaging the inner and outer sides of parallel rails, of an upstanding plate carried by the inner longitudinal edge of each base section and ar- 115 ranged in U-shaped formation, a wedge adapted to be received between the sides of said plate for forcing said rail-engaging means into engagement with said rails, and depending sides carried by said wedges and engaging the outer sides of said U-shaped 120 plates.

5. The combination with a pair of base

sections having means for engaging the inner and outer sides of a pair of parallel rails, of a U-shaped member arranged at one end of each base section and adapted 5 for receiving certain of said rail-engaging means, wedges adapted to be received within said U-shaped members and having one

end tapered for engaging the adjacent rail-engaging means, and depending arms carried by said wedges and arranged on opposite sides of said U-shaped members for bracing the same. 10

In testimony whereof I affix my signature.

JOSEPH LEVENTRY. [L. s.]
